UNITED STATES PATENT OFFICE

2,404,338

NOISE SUPPRESSION CIRCUITS

Joseph A. Worcester, Jr., Bridgeport, Conn., assignor to General Electric Company, a corporation of New York

Application August 20, 1941, Serial No. 407,543

23 Claims. (Cl. 250—20)

1

My invention relates to noise suppression circuits and it is particularly applicable to noise suppression circuits for automatically rendering the output circuits of a frequency modulation receiver inoperative when no signals are being received or when the received signals are too weak to provide satisfactory operation.

It is well known that objectionable noises may be emitted by the signal reproducer of a radio receiver during those intervals when no signals are being received, or while the receiver is being tuned between carrier channels. These noises may arise from a great many causes including cross-modulation effects, natural atmospheric static, locally produced high-frequency electrical disturbances, "shot" effects and thermal agitation in the tubes and circuits of the receiver itself, et cetera. Therefore, various squelch circuits have heretofore been proposed for muting the sound reproducer except when the receiver is tuned to a signal of sufficient strength to over-ride the noise level and provide satisfactory reproduction. The operation of such circuits has variously been designated by such terms as "background noise suppression," "inter-channel noise suppression" and "carrier-off noise suppression."

A properly designed frequency modulation receiver inherently provides a high signal to noise ratio so long as the received signals exceed a pre-determined level. This is due in large measure to the action of the amplitude limiting circuits which transmit the desired frequency modulation but discriminate against amplitude modulation. In order to realize the full possibilities of frequency modulation reception, it is common design practice to provide such a high degree of amplification in the high-frequency stages of the receiver that such effects as thermal agitation in the first tuned circuit and the "shot" effect in the first tube cause voltages to be impressed on the amplitude limiter approaching values required to saturate it. So long as any signal strong enough to operate the limiter is received, these voltages, as well as other undesired static and noise voltages and undesired amplitude modulation present in the signal, are reduced to a very low level at the limiter output and do not cause objectionable disturbances in the sound reproducer. However, in the absence of such signals it has been found that very substantial noise voltages appear in the limiter output and that, due to the extremely high sensitivity of the receiver and the frequency characteristics of the receiver circuits, the audible background noise may be very severe.

It is therefore highly desirable to incorporate

some form of noise suppression circuits for eliminating these background noises in a frequency modulation receiver in order that the full advantages of "static-less" operation may be realized. Accordingly, it is an important object of my invention to provide an improved background noise suppression circuit which is particularly adapted to the requirements of a frequency modulation receiver.

10 In a preferred embodiment of my invention, the noise voltages appearing as amplitude modulation in the limiter output under no-signal or weak-signal conditions, as explained above, are detected and utilized to provide bias potentials for reducing the transfer efficiency of a portion of the transmission channel following the limiter. Preferably, one of the amplifying stages following the limiter is completely blocked, and the sound reproducer effectively muted. However, as soon as a signal of sufficient strength for satisfactory operation is received (and such signal need be only a relatively weak signal just sufficient to saturate the limiter), the squelch voltage automatically collapses and the receiver operates at maximum sensitivity.

15 It is accordingly another object of my invention to provide an improved squelch or muting circuit, particularly adapted to the requirements of a frequency modulation receiver, whose operation is automatically determined by the character and magnitude of the voltages impressed thereon.

20 It is also a specific object of my invention to provide an improved carrier-off noise suppression circuit for frequency modulation receivers which is very sensitive and has a trigger action.

25 Still another object of my invention is to provide an improved automatic background noise suppression circuit which is economical and readily adapted to existing types of frequency modulators.

30 The features of my invention which I believe to be novel are set forth with particularity in the appended claims. My invention, itself, however, together with further objects and advantages thereof, may best be understood by reference to the following description taken in connection with the accompanying drawing, in which Fig. 1 is a schematic representation, partly in the form of a conventionalized one-line diagram, of a frequency modulation receiver embodying my invention; and Fig. 2 schematically represents modified forms of circuits embodying my invention which may be substituted for the corresponding portions of Fig. 1 within the dashed rectangle,

Corresponding reference numerals have been placed upon corresponding elements in the two figures to facilitate their comparison and simplify the accompanying description.

Before proceeding further with the description of the illustrated embodiments of my invention, I wish to explain the meaning of certain terms as used hereinafter in the specification and appended claims.

I intend such terms as "noise" or "noise voltages," unless otherwise qualified, to include all undesired voltages which may accompany the desired signals or be modulated upon them. For example, these voltages may be caused by cross-modulation effects, adjacent channel interference or non-linearities in the transmission channel; they may be caused by thermal agitation effects, "shot" effects, and related phenomena which occur in the receiver itself and give rise to disturbances of the so-called "continuous" or "hash" type; or they may be caused by natural atmospheric static, ignition interference, and the like, which occur outside the receiver and give rise to disturbances of the so-called "impulse" type.

By the term "amplitude modulation" I intend to include all amplitude variations in the envelope of high-frequency voltages appearing at specified points in the transmission channel, irrespective of the precise character of these voltages. Thus, for the purposes of my invention these voltages may constitute periodic signal voltages, either unmodulated or modulated in frequency or phase by desired signals, or irregular voltages such as are characteristic of any of the types of noise.

By the term "frequency modulation" I mean to include any form of modulation produced by varying the frequency or phase of a carrier wave as distinguished from modulation produced by varying the amplitude of such a wave.

The generic term "angle modulated" has been heretofore employed in the art in connection with waves of this character to indicate either frequency modulated or phase modulated waves or waves which are hybrids of the two. In the specific example described in the following discussion of the drawing, the received signal energy is assumed to be frequency modulated wave energy.

In the diagrammatic representation of a frequency modulation receiver shown in Fig. 1, many of the elements may be conventional and their details of construction are not material to my invention. Therefore, to simplify the drawing, such elements have merely been indicated in block form. Thus the receiver illustrated is for the most part a conventional superheterodyne receiver. Signals received at an antenna 10 are amplified in the usual radio frequency amplifiers 11 and combined in a mixer 12 with locally generated waves supplied from an oscillator 13. The carrier waves of fixed intermediate frequency are then amplified in intermediate frequency amplifiers 14. In frequency modulation receivers of usual design it is often the practice to pass the intermediate frequency waves through two amplitude limiters in cascade in order to secure a better limiting action. Thus in the illustrated embodiment some of the amplitude modulation is removed in a first limiter 15 and practically all of the remaining amplitude modulation is removed in a second limiter 16.

The intermediate frequency carrier waves at the output of the second limiter 16 are therefore of substantially constant amplitude and contain only the frequency modulation which is representative of the intelligence being transmitted,

e. g., audio signals. They are demodulated in a slope filter or discriminator 17. Various forms of apparatus suitable for this purpose are well known to the art. One type of frequency modulation detector circuit which I have found to be satisfactory is described in Patent No. 2,121,103—Seeley, granted June 21, 1938, to which reference may be made for further information.

The demodulated audio signals are supplied to 10 a first audio frequency amplifier 18, further amplified in an audio power amplifier 19, and then supplied to a suitable signal translating device, such as the loudspeaker 20.

The limiter 16 comprises a pentode amplifier 15, having an input circuit including a coupling capacitor 31 and grid resistor 32 connected between its control grid 33 and cathode 34, and an output circuit including a tuned circuit 35 connected to its anode 36. Anode operating potentials are supplied in conventional manner from a suitable source of power, which is not shown but merely indicated by the connection designated as "To +B" on the drawing, through the usual decoupling resistor 38. The screen grid 39 is similarly supplied with operating potentials from the common power supply source through a decoupling resistor 40.

The operation of the limiter 16 will be readily understood by those skilled in the art without detailed explanation. The limiter is self-biased by means of the capacitor 31 and the grid resistor 32. It is so adjusted as to pass anode current only between the limits at which positive grid current flows and at which anode current cutoff takes place.

In the form of my invention illustrated in Fig. 1, the anode 36 of the limiter 16 is also coupled to an amplitude detection circuit over a conductor 50. The circuit comprises a diode detector 51 shunted by a load resistor 52. The intermediate frequency potentials occurring at the anode 36 are impressed on the diode 51 through the conductor 50 and a capacitor 53. This detection circuit functions in a manner shortly to be described in greater detail. Briefly, it develops potentials across the load resistor 52 in accordance with amplitude modulation components appearing in the output of the limiter 16.

Potentials developed across the diode 51 are 50 impressed upon a second diode detector 54 through a capacitor 55, which removes direct current, and through a low-pass filter, comprising a resistor 56 and a capacitor 57, which removes intermediate frequencies.

The load for the diode detector 54 comprises a resistor 58. Unidirectional voltages appearing across this resistor are further filtered by a low-pass filter, comprising a resistor 59 and a capacitor 60, and impressed between the control grid 70 and cathode 71 of the first audio amplifier tube, which is illustrated as a triode 72. It will be observed that a conductive connection is provided between grid 70 and cathode 71 through a resistor 61 and resistors 58 and 59. These voltages are of such polarity as to bias the grid 70 negatively with respect to the cathode 71 and, as will shortly be explained, under certain conditions their magnitude is sufficient to reduce the amplification of the audio amplifier tube 72 to a very low level. Preferably tube 72 is thereby biased completely to cutoff, preventing transmission of signals to the power amplifier 19 and the loud speaker 20.

It has been found that there are always noise 75 voltages present at the second limiter even when

no voltages are impressed upon the receiver input. It has been demonstrated that the nature of these voltages is that of a spectrum containing an almost infinite number of component frequencies, some of which always coincide with the frequencies associated with the desired signals. It is generally accepted that irregularities in the motion of electrons in the tubes and circuits is largely responsible, i. e., the thermal agitation and "shot" effects and related phenomena. The first radio frequency amplifier stage undoubtedly contributes the greatest proportion of these disturbances because of the high gain provided in the stages between it and the limiter. Furthermore, it has been demonstrated that extraneous disturbances received at the antenna 10 also comprise an infinite frequency spectrum containing frequencies capable of being translated in the receiver channel. These disturbances further increase the voltage impressed upon the limiter under no-signal conditions.

As indicated earlier in this specification, it is preferable to provide such a high gain through the radio frequency and intermediate frequency amplifiers that the noise voltages impressed upon the limiter grid 33 develop self-bias potentials approaching values required to saturate the pentode 30 even under no-signal conditions. Nevertheless, under such conditions it has been found that these voltages are not appreciably limited in amplitude in the limiter 16 and that substantial noise voltages are developed at the limiter anode 36 including modulation frequencies within the audio band. Reception of external "static" disturbances at the antenna 10 merely increases their magnitude. However, as soon as a carrier signal is received which is sufficient to maintain the limiters continuously saturated, these voltages at the anode 36 almost completely disappear. In other words, so long as the received signal is strong enough to over-ride the noise level, voltages within the intermediate frequency band are continuously impressed upon the limiters to maintain them operative. Noise voltages alone, on the other hand, apparently contain no such continuous components, but are more like a highly over-modulated carrier of practically zero intensity and are not removed by the limiters.

In accordance with my invention these phenomena are utilized to provide background noise suppression in a manner now to be detailed.

In the embodiment of my invention illustrated in Fig. 1 the noise voltages appearing at the anode 36 are detected in the diode 51 and appear upon the load resistor 52. Preferably the time constant of this detector circuit is such that the noise voltages appearing on the resistor 52 lie within the audio range, higher frequency components being filtered out. It is desirable to use the audio noise voltages for control since voltages of these frequencies tend to be transmitted through the signal channel following the limiter and to cause audible disturbances in the loud speaker 20. Furthermore, voltages at frequencies within the intermediate frequency pass band are of course not removed by the limiters but are developed at the anode 36 even when signals of satisfactory strength are being received. Since noise voltages within this range cannot be readily distinguished from signal voltages, such higher frequency voltages must be filtered out in order for the desired control effect to be responsive to noise voltages alone.

The audio noise voltages are again detected in

the diode 54. The time constant of the network associated with this detector is made very long as compared to the period of the lowest audio frequency in the signal channel. The resulting unidirectional potentials, after being filtered to smooth them out further, are then utilized to provide the automatic squelch or muting bias for the audio frequency amplifier 10, as previously explained.

10 The modified form of my invention represented in Fig. 2 differs from that of Fig. 1 only in certain particulars. Corresponding elements have been designated by the same reference numerals and the function of these elements is essentially the same. Therefore, they need not be repeated here. In this modification the pentode 30 is itself utilized to detect the audio noise voltages present at the anode 36, permitting the first diode detector to be eliminated. This is possible because the time constant of the grid circuit 31, 32 15 is such that the pentode 30 functions essentially as a grid power detector for amplitude modulation components within the audio frequency band. Therefore, it produces audio voltages across an audio frequency load in the anode circuit. Such a load is provided by the decoupling network comprising the capacitor 37 and decoupling resistor 38. Consequently, the audio noise voltages appear at the point 13 and may be supplied directly to the filter and detector network 20 25 30 55-60, as illustrated.

In a frequency modulation receiver of commercially acceptable sensitivities, the audio noise voltages at the point 13 have been found to be at least of the order of 10 volts under all operating conditions. This provides a unidirectional squelch voltage of at least four volts at the grid of the audio amplifier 12, which is sufficient to cut off a typical high-mu triode driver tube. Extraneous noise voltages received at the antenna 10 further increase these values so that the squelch voltage is automatically increased when the receiver is operated in excessively noisy locations.

40 45 50 55 As soon as even a relatively weak signal is received the squelch voltage immediately collapses and the receiver operates at full sensitivity. Such a signal need be only of a few microvolts intensity, i. e., just sufficient to render the limiters fully effective. As previously explained, the background noise at the loud speaker is now reduced to a very low level through the inherent capabilities of this type of system to discriminate between signals and noise and to reject the latter.

55 60 65 It will therefore be apparent that my invention combines a highly sensitive background noise suppression action with a fast-acting trigger action. Furthermore, the noise suppression circuit is also effective in removing side responses caused by the slope characteristics of the sides of the intermediate frequency response curve. If the receiver is mistuned or misaligned, frequency modulation signals will be detected in the intermediate frequency circuits through well known slope filter action, producing amplitude modulation signals across the limiter anode resistor and resulting in the production of a squelch bias in the same manner as noise voltages.

70 For completeness of illustration only, and not in any sense by way of limitation, the following circuit constants are given as being typical for a frequency modulation receiver of the type represented in Fig. 2. These constants have been found to be satisfactory for the circuit elements of a frequency modulation broadcast receiver

adapted to receive signals in the vicinity of 42 to 50 megacycles and having an intermediate frequency channel tuned to about 4.3 megacycles. In this particular receiver the tube 30 was a type 6SJ7 pentode and the audio frequency amplifier 72, the diode 51 and the diode 54 were all embodied in a single duo-diode, high-mu triode, type 6SQ7. Other circuit constants follow:

Capacitor 31	mmf	22
Resistor 32	ohms	180,000
Capacitor 37	mmf	47
Resistor 38	ohms	22,000
Capacitor 55	mfd	.01
Resistor 56	ohms	10,000
Capacitor 57	mmf	100
Resistor 58	megohms	1
Resistor 59	do	2.2
Capacitor 60	mfd	.01
Resistor 61	megohms	6.8

While I have shown particular embodiments of my invention, it will of course, be understood that I do not wish to be limited thereto since various modifications may be made, and I contemplate by the appended claims to cover any such modifications as fall within the true spirit and scope of my invention.

What I claim as new and desire to secure by Letters Patent of the United States is:

1. In combination, a signal channel for translating signal-bearing waves, amplitude limiting means in said channel effective substantially to remove amplitude modulation from waves impressed thereon only so long as a predetermined limiting level is exceeded, and means responsive to amplitude modulation in waves in the output of said limiting means for disabling subsequent portions of said channel comprising means for rectifying said amplitude modulation to produce a control voltage varying in accordance with the magnitude of said modulation.

2. In combination, a signal translating channel having means therein adapted to translate frequency-modulated high-frequency waves, said means also being effective to supply substantial noise voltages to its output, amplitude-limiting means coupled to said translating means to limit the amplitude of high frequency waves supplied through said limiting means, said amplitude-limiting means having amplitude modulation components due to said noise voltages developed in its output when said high-frequency waves supplied therethrough are of intensity less than a predetermined level, said modulation components being substantially removed from its output so long as the intensity of said waves exceeds said level, means for detecting said components and deriving a unidirectional potential therefrom, and means responsive to said unidirectional potential for substantially reducing the transfer efficiency of said channel.

3. In combination, a signal amplifier adapted to amplify high frequency voltages modulated in frequency in accordance with a band of signal frequencies, said amplifier having undesired noise voltages of interfering frequencies continuously present in its output, an amplitude limiter coupled to said amplifier, said limiter being effective to remove amplitude modulation, at signal frequencies, from said voltages only so long as high frequency voltages exceeding a predetermined limiting level are supplied from said amplifier, output circuits coupled to said limiter, said circuits including an amplifying device having a control electrode, an amplitude modulation

detector also coupled to the output of said limiter, and means for biasing said control electrode in response to voltages developed by said detector and in a sense to reduce the amplification of said device.

4. In a frequency modulation receiver, the combination comprising a signal amplifier, an amplitude limiter coupled to said amplifier, output circuits coupled to said limiter, said circuits including an electron discharge device having a control electrode, an amplitude modulation detector connected to the output of said limiter, and means for biasing said control electrode in response to modulation voltages developed by said detector to prevent translation of said signals by said electron discharge device.

5. In combination, a signal amplifier adapted to amplify high frequency voltages modulated in frequency in accordance with a band of signal frequencies, said amplifier having such a high gain that undesired noise voltages of interfering frequencies are continuously present in its output, an amplitude limiter coupled to the output of said amplifier, said limiter being effective to remove amplitude modulation, at signal frequencies, from said voltages only so long as high frequency voltages exceeding a predetermined limiting level are supplied from said amplifier, a signal reproducer coupled to said limiter, and means responsive to amplitude modulation at signal frequencies in the output of said limiter for preventing operation of said reproducer.

6. In radio receiving apparatus for operation on high-frequency waves modulated in frequency in accordance with a band of signal frequencies, the combination comprising a thermionic amplifier for said waves having such a high gain that undesired noise voltages of interfering frequencies, due to received disturbances, thermal agitation, shot effects, and the like, are continuously present in its output, an amplitude limiter coupled to said amplifier comprising a thermionic device having an output electrode, said limiter being of such a character that amplitude modulation components at signal frequencies are continuously present in potentials appearing on said electrode so long as received high-frequency waves do not exceed a predetermined limiting level but are reduced to a negligible value so long as said waves exceed said level, signal translating circuits including a signal reproducer coupled to said electrode, an impedance element coupled to said electrode and adapted to have voltages of signal frequencies developed thereon in response to said components, and means for muting said signal reproducer in response to said last-named voltages.

7. In radio receiving apparatus for translating high-frequency waves modulated in frequency by desired signals, the combination comprising thermionic means for amplifying received waves to such a high level that substantial undesired noise voltages of the frequencies of said signals and due to received disturbances, thermal agitation, shot effects, and the like, are developed, amplitude limiting means coupled to said amplifying means, said last means being effective to reduce said undesired voltages to a very low level in its output only so long as high-frequency waves exceeding a predetermined minimum limiting level are impressed on its input, means coupled to said output for translating said high-frequency waves, and means responsive to said undesired voltages appearing in said output for disabling said translating means comprising means for rectifying

said voltages to produce a control voltage varying in accordance with the magnitude of said undesired voltages.

8. In a frequency modulation receiver of the type comprising high frequency amplifiers for amplifying waves modulated in frequency by desired signals, an amplitude limiter, a frequency demodulator, a low frequency signal amplifier and a signal reproducer, wherein said high frequency amplifiers provide sufficiently high amplification that undesired noise voltages are continuously supplied to said limiter, and wherein said limiter is effective substantially to prevent transmission of noise voltages therethrough only so long as said waves exceed a predetermined limiting level, a noise suppression circuit comprising means for detecting noise voltages transmitted through said limiter, means for rectifying said detected voltages to provide unidirectional control potentials, and means for utilizing said control potentials to prevent transmission of noise voltages from said limiter to said signal reproducer.

9. In radio receiving apparatus adapted to translate high-frequency waves modulated in frequency by desired audio frequency signals, the combination of means for limiting the amplitude of said frequency modulated waves to a substantially constant level, said means comprising a thermionic device having an anode circuit, frequency modulation signal detecting means coupled to said anode circuit, an electron discharge amplifier coupled to the output of said detecting means, said amplifier having a control element, means comprising a diode detection circuit for developing audio frequency voltages in response to audio-frequency amplitude modulation components present in waves developed in said anode circuit, means comprising a second diode detection circuit for developing a unidirectional control potential in response to said audio frequency voltages, and means for biasing said control element negatively in accordance with said control potential.

10. In radio receiving apparatus adapted to translate high-frequency waves modulated in frequency by desired audio frequency signals, the combination of means for limiting the amplitude of said waves to a substantially constant level, said means comprising a self-biased thermionic limiter having an anode circuit, frequency modulation signal detecting means coupled to said anode circuit and an audio frequency amplifier coupled to the output of said detecting means, said audio frequency amplifier having a grid electrode, a resistance-capacitance network in said anode circuit adapted to have audio frequency noise voltages developed therein, means comprising a diode detection circuit for developing unidirectional control potentials in response to said noise voltages, said circuit having a time constant longer than the period of the lowest desired audio frequency, and means for biasing said grid electrode negatively in accordance with said potentials.

11. In a receiver for carrier waves frequency modulated by desired signals in which the received carrier waves are first amplified to intensity in excess of a predetermined value and then transmitted through a limiter which limits said waves to a uniform intensity of said value, the method which comprises rectifying noise voltages of the frequencies of said signals and which appear at the output of said limiter during periods of reduced signal intensity, and controlling the

output from said receiver in accord with the rectified noise voltages.

12. In a receiver for carrier waves frequency modulated by desired signals in which the received carrier waves are first amplified to intensity in excess of a predetermined value and then transmitted through a limiter which limits said waves to a uniform intensity of said value, the method which comprises controlling the output from said receiver in accord with noise voltages of varying amplitude and of the frequencies of said signals appearing at the output of said limiter during periods of reduced intensity of the received carrier wave.

13. The combination, in a receiver for frequency modulated carrier waves of an amplifier for frequency modulated carrier waves, a limiter to limit waves amplified by said amplifier to a predetermined value, said amplifier having amplification sufficient to produce noise voltages of objectionable intensity and variable amplitude at the output of said limiter in the absence of received carrier waves, said noise voltages disappearing from said output in the presence of received carrier waves of greater than a predetermined intensity, and means to disable said receiver in response to the amplitude variations of said noise voltages at the output of said limiter.

14. The combination, in a receiver for frequency modulated carrier waves, of an amplifier for signal modulated carrier waves, a limiter to limit waves amplified by said amplifier to a predetermined value, said amplifier having amplification sufficient to produce noise voltages of objectionable intensity at the output of said limiter in the absence of received carrier waves, said noise voltages disappearing from said output in the presence of received carrier waves of greater than a predetermined intensity, a rectifier, means to supply said noise voltages to said rectifier, said means including means to eliminate voltages of the frequency of the carrier wave amplified by said amplifier, and means responsive to rectified voltages produced by said rectifier to disable said receiver.

15. The combination, in a frequency modulation receiver, of an amplifier for frequency modulated carrier waves, a limiter to limit waves amplified by said amplifier to a uniform intensity, a rectifier connected to rectify noise voltages at the output of said limiter, a second rectifier, means to supply variations in voltage at the output of said first rectifier to said second rectifier and to prevent said carrier waves from reaching said second rectifier, and means responsive to the rectified voltage produced by said second rectifier to reduce the output from said receiver.

16. In a receiver of angle modulated carrier wave energy of the type provided with an amplitude limiter stage, a demodulator and a modulation signal amplifier; the method which comprises detecting from the output of said limiter noise voltage components when the received signal-to-noise ratio is excessively low, rectifying the detected noise voltage components to provide a control voltage, and impairing the operation of said modulation signal amplifier in accordance with said control voltage.

17. A method of receiving frequency modulated waves which comprises limiting the amplitude of the waves, demodulating the limited waves, amplifying the demodulated wave energy, detecting from the limiter output noise voltage components in response to the decrease of received wave energy below a usable value, deriving from the de-

ected noise voltage components a control voltage, and preventing said amplification of the demodulated wave energy in response to said control voltage.

18. In a receiver of angle modulated carrier wave energy of the type provided with an amplitude limiter stage, the method which comprises detecting from the limiter output noise voltage components when the received signal-to-noise ratio is excessively low, rectifying the detected components to provide a control voltage, and utilizing the control voltage to impair receiver reproduction.

19. A method of receiving frequency modulated waves which comprises limiting the amplitude of the waves, detecting from the limiter output noise voltage components in response to the decrease of received wave energy below a usable value, deriving from the noise voltage components a control voltage, and preventing reproduction of the wave energy in response to said control voltage.

20. In a method of frequency modulation reception wherein the amplitude of frequency modulated carrier waves is limited in a limiter prior to detection; the improvement which comprises deriving a control voltage from amplitude modulation appearing in the output of the limiter when the received signal to noise ratio is below a predetermined threshold level, and suppressing the reproduction of detected energy in response to said control voltage thereby to prevent reproduction of noise.

21. In the operation of a receiver of angle modulated carrier wave energy which comprises an

amplitude limiter, a detector and a modulation amplifier; the improvement which comprises rectifying amplitude modulation noise energy appearing in the limiter output when the angle modulated energy decreases to a level such that peak carrier voltage is substantially equal to peak noise voltage, deriving a muting bias voltage from the rectified noise energy, and suppressing operation of the amplifier with the bias voltage.

22. In a frequency modulation receiver of the type having an amplitude modulation limiter, a detector and an audio amplifier; the improvement which includes means for detecting amplitude modulation appearing in the limiter output energy in response to adjustment of the tuning of said receiver between stations; means for rectifying the noise modulation produced as a result of said detection, and further means for muting said audio amplifier with the rectified voltage thereby to prevent the rush of noise commonly produced during absence of carrier.

23. A system of receiving angle modulated carrier energy including means limiting the energy to reduce amplitude modulation effects, means demodulating the limited energy, means for amplifying the demodulated energy, means deriving a control voltage from amplitude modulation noise energy appearing in the output of said limiting means when the received modulated carrier energy decreases below a predetermined threshold, and means for inhibiting said amplification with said control voltage.

JOSEPH A. WORCESTER, JR.
